UNITED STATES PATENT OFFICE.

HENRY D. SCHMIDT, OF GALVA, KANSAS.

GRAIN-HARVESTER.

980,347.

Specification of Letters Patent.

Patented Jan. 3, 1911.

Application filed December 15, 1909. Serial No. 533,242.

To all whom it may concern:

Be it known that I, HENRY D. SCHMIDT, a citizen of the United States, residing at Galva, in the county of McPherson and 5 State of Kansas, have invented certain new and useful Improvements in Grain-Harvesters, of which the following is a specification.

This invention relates to harvesters, and 10 is especially applicable to that kind thereof known as headers which are pushed from behind by suitable power. Such machines have heretofore been made in which the propelling and driving power was furnished 15 by a team, or by an engine such as a gasoline engine.

The object of my invention is to provide 20 a horse propelled machine with a gasoline or similar engine for the purpose of driving the operative parts such as the cutting apparatus, the grain platform, and the elevator, and also the binder when the machine includes binding mechanism.

The improvement will be particularly 25 useful when the grain is wet or the going is heavy, means being provided to throw the engine in or out of gear when its power is not needed, in which event the devices referred to will be driven by the horse power 30 as heretofore.

In the accompanying drawings, Figure 1 is a plan view of an ordinary header showing the engine and other parts applied thereto, some parts and details being omitted 35 as unnecessary for this disclosure. Fig. 2 is a section on the line 2—2 of Fig. 1.

Except as hereinafter described the structure of the machine may be of any suitable or desired kind, and referring specifically 40 to the drawings, 1 indicates the two main driving and supporting wheels which are mounted on and carry the main axle 7. The thrust tongue 13 is rigidly attached at its front end to the sleeve casing 17 of the axle 45 and projects rearwardly therefrom as usual, and is provided near its rear end with the whiffletree 14 to which the draft animals are attached, as well as with an operator's platform 15, and the rear caster wheel 16 by 50 which the machine is guided or turned. The axle casing supports the frame of the machine which is illustrated as consisting of longitudinal bars 18 and front and rear cross bars 19.

55 Mounted on the axle is a sprocket wheel 2 around which passes a chain 20 which

drives a sprocket 3 loose on a counter or cross shaft 8 supported in suitable bearings on the longitudinal bars 18. From the stubble end of the countershaft 8 motion is 60 communicated to the cutting mechanism 21, as well as to the platform 22, elevator 23, and to a binder if used, by means of gearing or transmission devices which need not be particularly described, and which may be 65 such as are suitable for the purpose and as are found in ordinary machines.

Feathered upon the shaft 8 is a clutch member 6 arranged to coöperate with a clutch member 24 fastened to or made integral with the wheel 3, and the clutch member 6 is shifted to engage or disengage the clutch by means of a bent lever 25 and a rod 26 connected to the hand lever 27 which is conveniently located adjacent to the platform 15. When the clutch referred to is shifted into engagement the cutting and other mechanisms will be driven from the main axle, in consequence of the traction of the supporting wheels, as in the ordinary har- 80 vester.

Conveniently mounted upon the axle casing 17, adjacent the front end of the thrust tongue, is a gasoline or other engine 4, the fly or other wheel of which is connected by 85 a belt 30 to a clutch wheel 31 loose on the countershaft 8. The engine may be of any desired construction.

Feathered upon the shaft 8 is a shaft or clutch member 10 arranged to engage the 90 clutch wheel 31, and operated by means of a lever 32 connected by a rod 33 to a hand lever 28 adjacent the operator's platform.

By the means described the cutting mechanism and other parts of the harvester may 95 be operated by the gasoline engine, and to do this, the clutch 6 is first disengaged and the clutch 10 engaged. Then, the machine will be propelled by the team, and the countershaft 8 and the mechanisms driven thereby will be driven by the gasoline engine; or, reversely, the engine may be disconnected and the ordinary driving gear connected for said purpose.

The aid of the engine will be found par- 105 ticularly desirable when the grain is wet or heavy, or when the machine is operating in soft soil.

What I claim as new is:—

In a harvesting machine, the combination 110 with a frame, axle and traction wheels supporting the frame, draft devices for draft

2
animals located behind and connected to the frame, and harvesting mechanisms carried by the frame at the front thereof, of a cross shaft mounted on the frame between the axle and said mechanisms, transmission gearing including a clutch between said axle and shaft, an engine supported on the frame behind said cross shaft, transmission gearing including a clutch between said engine and shaft, both of said clutches being opera-

tively located on the shaft, and means to engage and disengage the respective clutches, whereby said mechanisms may be driven by either the wheels or the engine.

In testimony whereof, I affix my signature 15
in presence of two witnesses.

HENRY D. SCHMIDT.
